STEEL GIRDERS

Kurt Hecker, Paul Jordan, and Willy Kaiser, Frankfurt am Main, and Herbert Vögeli, Neu-Isenburg, near Frankfurt am Main, Germany

Application July 3, 1951, Serial No. 234,930

Claims priority, application Germany July 4, 1950

3 Claims. (Cl. 189—37)

This invention relates to improvements in steel girders for use in steel-concrete construction.

The use of steel girders for floors and ceilings is known, which girders take the form of simple I sections, Z-steel, or light lattice girders, if desired with perforations in the web or main body, others consisting of angle-sections, and like sections in combination with corrugated plates or the like. However, the known girders neither save weight nor are they susceptible to be economically produced.

It is an object of this invention to provide light steel girders capable, when assembled and without being enclosed in concrete, to take up the entire natural load and an additional useful load.

A further object of this invention is to save material in the production of steel girders and to decrease construction costs wherever steel girders are used.

Other objects of the invention will become apparent in the course of the following specification.

In the attainment of these objectives, the improved girders are made in three embodiments. In the first embodiment, two spaced sheet metal elements which may be less than 4 mm. in thickness are used and in which coacting strips, partially cut out of the web or main body of the elements, are drawn inwardly between the elements to form engaged protuberances which are secured together. The second embodiment is like the first except that rather than having the inwardly drawn strips or protuberances for connecting the two elements, the protuberances take the form of tongues stamped out of the webs or main bodies of the elements and then bent inwardly toward the opposite element for attachment thereto. The third form of the improved girders is also like the first except that the protuberances take the form of coacting bulges formed in the web or main body of each element with the crests of the bulges meeting between the elements and fastened together.

The invention will appear more clearly from the following detailed description when taken in conjunction with the accompanying drawings showing by way of example, the preferred embodiments of the inventive concept.

In the drawings:

Figures 1-3 show the first embodiment of the improved girder constructed in accordance with the principles of the invention and in which:

Figure 1 is a fragmentary side elevational view of the girder;

Figure 2 is an end view of the girder shown in Figure 1; and

Figure 3 is a plan view of the girder shown in Figure 1.

Figures 4-6 shows the second embodiment of the improved girder, and in which:

Figure 4 is a fragmentary side elevational view of the girder;

Figure 5 is an end view of the girder shown in Figure 4; and

2

Figure 6 is a plan view of the girder shown in Figure 4. Figures 7-9 show the third embodiment of the improved girder, and in which:

Figure 7 is a fragmentary side elevational view of the girder;

Figure 8 is an end view of the girder shown in Figure 7; and

Figure 9 is a plan view of the girder shown in Figure 7.

Figure 10 is a sectional view through a steel-concrete joist ceiling having filling elements and showing diagrammatically the use of the improved girders.

Referring now in greater detail to the first embodiment of the improved girders shown in Figures 1-3, reference numeral 1 indicates two strip steel elements or sections, 4 lengthy formations or protuberances partially severed from the web or main body of the steel sections, and 4a transverse reinforcement beads.

Each of the two spaced steel sections 1 at the bottom is turned outwardly to form the flange 2 at 90° to the plane of the main body, and at the top to form an outwardly and upwardly turned edge 3 forming an obtuse angle with the plane of the main body as illustrated.

Aligned strips 4 are partially cut out of the main body of each section along the lines 4b and 4c (Fig. 1), the partially severed portion being then drawn inwardly to form protuberances in engagement with or aligned with similar protuberances on the opposite section. Each pair of engaged protuberances are then joined together

30 by any known means such as spot or bead welding, riveting, flanging, or by means of clips. As is shown in Figure 3, a lattice-like interconnection of the two sections is thus obtained. The transverse beads 4a are pressed from the main bodies intermediate the protuberances for reinforcement purposes.

In the second embodiment of the improved girders shown in Figures 4-6, the construction is the same as that previously described for the first embodiment except that in place of the inwardly drawn strips or protuberances of the first embodiment, the protuberances take the form of the tongues 5 which are stamped out of the main body of each section, for example, along the lines 5a and 5b and 5c, the spaced lines 5a and 5b being intersected by the line 5c. The partially severed portions are then bent inwardly to engage the opposite section to which attachment is made by any suitable means. Of course, the tongues of each section will be in staggered relationship as most clearly shown in Figures 4 and 5 rather than being in aligned or opposed relationship as the strips of the previously described first embodiment.

In the third embodiment of the improved girders shown in Figures 7-9, the construction is also the same as that of the first embodiment except that in place of the strip protuberances of the first embodiment, the protuberances of the third embodiment take the form of arcuate bulges 6 formed in the web or main body of each element or section by being inwardly rolled. However, the bulges of each section are aligned to form coacting pairs meeting substantially at the highest point of the crests and then fastened together in a known manner. Between the bulges are the reinforced apertures 7 with thick outwardly extending flanged edges along the upper part of the sections and between the bulges.

65 The rectangular apertures created in the main bodies of the sections in the formation of the strip and tongue protuberances of the first and second embodiments ensure an intimate uniform connection of the concrete introduced so that thrusts and shear stresses are taken up.

60 The filling of the bulge protuberances of the third embodiment with concrete affords security against thrusts and shear stresses. The outward flanging of the aper-

tures 7 in the upper part of each section or element of the same embodiment provides a considerable increase in resistance to bulging while the bulges b, formed by cold deformation, produce an increase in the strength of the material employed.

The formation by rolling of the transverse beads 4a, as shown in the first and second embodiments, and even in the third embodiment (not shown) will further increase the strength of the girder.

As illustrated in Figure 10, the improved steel girders are used as joist reinforcements for ceilings. The hollow filling elements 8 bear on the lower flanges of two of the girders and form the filling between the girders, and, at the same time, the shuttering for the rib concrete or the end concrete which is introduced after the completion of the assembly and in which subject girders are embedded as reinforcements. It will be noted in Figure 10 that each of the filling elements 8 have a bottom ledge 9 extending under the girder over the entire width thereof. The narrow slot remaining between the girder flanges and the bottom ledges 9 can only be filled with concrete because sufficient space is left for the passage of the concrete between the spaced metal sections 1.

It will be obvious that the new girder is susceptible of a wide variety of modifications and alterations within the scope of the appended claims.

What is claimed is:

1. A girder and like structure comprising two elongated plates having surfaces substantially parallel to and spaced from each other, both said plates having spaced apart first protuberances of substantially equal configuration and extending in transverse direction to the plates and recessed in said surfaces thereof, and second protuberances in the form of tongue members of substantially equal length struck out of the material of said plates and arranged to extend in lengthwise direction thereof and within the space between two adjacent transversely extending first protuberances, said tongue members of one plate being disposed alternately in one of two parallel, longitudinal rows, the tongue members of the other

plates from each other.

2. A girder and like structure comprising two elongated plates having surfaces substantially parallel to each other, both said plates being provided with spaced apart first protuberances of substantially equal configuration and extending in transverse direction to the plates and recessed in said surfaces thereof, and second protuberances forming tongue members substantially equal in length and struck out of the material of each plate, said tongue members being bent angularly to said plates toward an opposed plate and being oriented in the lengthwise direction thereof and disposed between two adjacent transverse first protuberances of each plate, said tongue members of said plates terminating in free ends, said tongue members of one plate extending in planes parallel to each other and being arranged alternately in one of two parallel longitudinal rows, the tongue members of the other plate extending in planes parallel to each other and intersecting with the planes in which said tongue members of said one plate extend, and bonding means attaching the respective free ends of said tongue members to said surfaces of said plates to space the same at a predetermined distance from each other.

3. A girder according to claim 2, whereby the opposite sides of said plates are bent angularly to the remainder of said plates.
